JOSEPH BRAUTIGAM AND PHILIPP HOELZLEIN, OF BROOKLYN, NEW YORK.

ENGINE.

SPECIFICATION forming part of Letters Patent No. 699,141, dated May 6, 1902.

Application filed July 8, 1901. Serial No. 67,399. (No model.)

To all whom it may concern:

Be it known that we, JOSEPH BRAUTIGAM and PHILIPP HOELZLEIN, citizens of the United States, and residents of Brooklyn, in 5 the city and State of New York, have invented certain new and useful Improvements in and Pertaining to Engines, of which the following is a specification.

Our invention relates to improvements in 10 engines, and more particularly to means and method of operating engines employing a piston that is not subject to operating pressure in every cycle of movement thereof.

It is a common device to admit pressure 15 upon the piston of certain engines at every fourth stroke only or other suitable interval, the weight of the running parts serving in the meanwhile to keep up the motion. This method is more especially adapted to engines 20 that are operated by the expansive force of a gas, the resultant of an explosion brought about in any one of several ways, as the ignition of an explosive solid or explosive admixture of gases. While such engines may be 25 double-acting, the pressure operating alternately on opposite sides of a piston, a usual practice is to provide a single-acting cylinder with means for directing the gas resultant from an explosion upon the inner side of said 30 piston to force it outwardly, thus driving the fly-wheel, if that contrivance be employed. Suitable mechanism will thereafter cause the explosion contrivances to become inoperative until the required number of strokes have 35 elapsed or until in some cases the speed of the fly-wheel is reduced to a predetermined point, when a new explosion will occur. There will be an exhaust for the cylinder to provide for the escape therefrom of air or 40 gas on the return-stroke of the piston. It is to an engine of this class that we have shown our invention applied in the drawings.

We will first describe an engine embodying 45 our invention and then point out its novel features in the claims.

Figure 1 is a side elevation, partly in section, of a device embodying our invention, together with a sufficient portion of an engine to clearly illustrate its operation. Fig. 2 is a 50 detached view, on an enlarged scale, of the catch shown in Fig. 1 for carrying out our invention.

Similar letters of reference designate corresponding parts in the figures of the drawings.

55

A represents the main shaft of an engine embodying our invention. B represents a fly-wheel thereon.

60

C represents the cylinder, preferably open at the end thereof nearest the shaft A.

D represents a valve-chest adjacent the cylinder C.

65

E represents a connecting-rod connected with a piston within the cylinder C and with a crank e on the shaft A.

The construction of the valve-chest D is as follows: A main chamber at F connects by a port f with the interior of cylinder C. An upper chamber at G is connected through pipe G' with a gas-supply (not shown) and 70 through an opening at g with the main chamber F. A lower chamber H is connected with pipe H' for the purpose of exhausting or allowing escape of compression and through opening at h with the main chamber 75 F. A chamber I is open to the atmosphere through pipe I' and connected through opening at i with the main chamber F. The said chambers F G H I are formed for convenience in juxtaposition. A cover (not 80 shown) will be attached to close said chambers from the atmosphere.

J represents a valve-rod with valve at j and passing through chamber G at g' for closing the port or opening g, and a spring J', bearing upon a collar j' on the rod J, normally keeps said port closed. Similarly the port h in chamber H is normally closed through the action of spring K' bearing on a collar k' on a valve-rod K, the valve k adapted to close 90 said port h, but shown open. In like manner L represents a valve-rod with valve l for closing port i in chamber I, spring L' acting on collar l' to keep said valve normally closed. The spring L' will be of comparatively light 95 tension.

A preferable construction for actuating valve-rod J is as follows: On shaft A is a pinion M, engaging a gear M', having double the number of teeth and which is provided with a cam N for actuating the rod J. Therefore the valve J can never be operated more than once for every two cycles of piston movement. m represents a fixed bracket provided with 100

bearings for a horizontal slide N' , that is provided with a roller n for engaging cam N and a spring n' to maintain the two in contact. A vertical arm O upon slide N' has pivoted at o 5 a part consisting of a horizontally-extending portion O' , forming an arm for actuating rod J , and an upwardly-extending governor device. This latter device comprises a weight P and a screw-threaded adjusting-rod P' , having nuts $p\ p$ and a spring p' to cause an upward pressure regulated by means of screw p' and tending to force weight P to the left in Fig. 1. On valve-rod J is an enlarged portion Q , engaging a bearing-surface on bracket Q' , 10 and this portion Q is provided with projection or notch q for engaging with arm O' . On gear M' is also provided a cam R for engaging a roller R' on the part r of valve-rod K , which part r is supported in bearings in bracket m . 15 The arrow shows the direction of rotation of pinion M . Gear M' consequently rotates in the reverse direction, wherfrom it will be seen that valve-rod K will be operated by its cam after the rod J .

20 S represents a catch-lever pivoted to bracket Q' and extending horizontally, preferably between the rods J and K , and it is provided with a catch s , adapted to engage a projection or notch r' on rod K when valve k is open, so as 25 to hold the same open against the force of spring K' . Said catch-lever is also provided with a cam at s' for engaging a roller q' upon rod J , the roller effecting the lifting of the lever S when the rod J is moved through cam N . 30 In Fig. 2 is shown the catch-lever with the cam s' thereon adjustable through screw S' , passing through the slot indicated in dotted lines.

35 The operation may be as follows: The parts 40 are in the position they will occupy when the valve j is just about to open. Should the fly-wheel be turning at an excessive speed, the force of the cam N in moving slide N' will cause the weight P of the governor to sag backward, compressing spring p' and elevating arm O' , so that it will pass over notch q on valve-rod J , thereby preventing the operation of valve j . After two, four, or other 45 number of strokes, however, when the speed 50 is reduced so that the governor may act to effect the engagement of arm O' and rod J , which, as stated, is the condition shown in Fig. 1, the continued movement of slide N' will effect the 55 opening of valve j , thereby admitting gas to the cylinder C . Simultaneously the roller q' , engaging cam s' on lever S , effects the release of rod K to close valve k , this being about to occur. The piston in cylinder C then operates to draw gas into the cylinder and, as well, 60 a certain proportion of air through valve l to form an explosive mixture. A means controlling the amount of air to be admitted may be employed, if desired. When the piston moving into the cylinder compresses the 65 explosive mixture and is about to move outward

again, the explosion takes place. This may be by any suitable or well-known contrivance, such as we have illustrated at T , t being the usual chimney and t' an auxiliary gas-supply for the igniting-jet. This device need not be 70 further described. The explosion forces the piston outward, actuating the fly-wheel and increasing its speed slightly. At or before the return stroke immediately following cam R engages roller R' to open valve k . At this 75 time our device or catch operates to engage and hold open the valve k or exhaust, thereby on the succeeding strokes permitting a free movement of air or gas into and out from cylinder C , decreasing resistance to the movement of the piston, as before stated. 80

What we claim as our invention is—

1. In a gas-engine, the combination with a cylinder and a piston therein, of an exhaust-valve, means for exploding the gas behind the 85 piston, said explosions taking place at intervals less frequent than one for every cycle of piston's movement, means for opening the exhaust behind said piston to exhaust the gas after sufficient explosion thereof, an inlet-valve for the explosive mixture, a rod for operating said inlet-valve, an arm for engaging and moving said rod, a governor connected with said arm, a slide carrying the arm and governor and a cam for moving said slide, 90 substantially as herein shown and described.

2. In a gas-engine, the combination with a cylinder and a piston therein, of an exhaust-valve, means for exploding the gas behind the piston, said explosions taking place at intervals less frequent than one for every cycle of piston's movement, means for opening the exhaust behind said piston to exhaust the gas after sufficient explosion thereof, an inlet-valve for the explosive mixture, a rod to which 100 said valve is attached, a pivoted arm, a slide carrying said latch and governor, a cam for actuating the slide, a rod carrying the exhaust-valve, a catch engaging said rod and means on the rod of the inlet-valve for operating said 110 catch and a separate cam for operating the exhaust-valve, substantially as herein shown and described.

3. In a gas-engine, the combination with a cylinder and piston, of an exhaust-valve and 115 an inlet-valve, two cams driven from the main shaft, means for actuating the inlet and exhaust valves by said cams, means for locking the exhaust-valve in open position, and means operated in connection with the inlet-valve 120 for unlocking the exhaust-valve, substantially as herein shown and described.

In testimony whereof we have signed our names to this specification in the presence of two subscribing witnesses.

JOSEPH BRAUTIGAM.
PHILIPP HOELZLEIN.
